PLUMBING FIXTURE

James W. McGarry, Waterbury, Conn., assignor
to Chase Brass & Copper Co. Incorporated, Waterbury, Conn., a corporation of Connecticut

Application November 2, 1939, Serial No. 302,491

11 Claims. (Cl. 277—50)

The present invention relates to improvements in plumbing fixtures and more particularly to plumbing fixtures having a plurality of valves for controlling the flow of water to other plumbing fixtures such, for instance, as a shower-head.

One of the objects of the present invention is to provide a superior plural-valve plumbing fixture in which the supply of water of the desired volume may be directed to a shower fixture or other plumbing fixture without affecting or altering the selected temperature of the water.

Another object of the present invention is to provide a plural-valve plumbing fixture having superior means incorporated therein whereby the desired volume of water at a pre-selected temperature may be quickly and easily controlled without requiring resetting of the individual hot-water and cold-water valves.

A further object of the present invention is to provide a superior plural-valve plumbing fixture having incorporated therein positive volume-control means for controlling the volume of water to a shower fixture or the like, and which is effective and economical to manufacture.

Still another object of the present invention is to provide a superior water-control unit embodying in compact and effective relationships, individual hot-water control-means, individual cold-water control-means, and means for varying the combined output of both of the other said means, without disturbing the relative percentages of hot and cold water in the outflow from the unit.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in front elevation of a plural-valve plumbing fixture embodying the present invention and shown as installed in a wall structure;

Fig. 2 is a side view thereof with portions of the wall structure shown in vertical section;

Fig. 3 is a broken vertical sectional view taken on the line 3—3 of Fig. 1 but on a larger scale;

Fig. 4 is a similar view taken on the line 4—4 of Fig. 1;

Fig. 5 is a fragmentary sectional view taken on the line 5—5 of Fig. 3;

Fig. 6 is a view in front elevation of the distributing-head;

Fig. 7 is a broken horizontal sectional view taken on the line 7—7 of Fig. 6; and

Fig. 8 is a perspective view of the volume-control valve-head.

The particular plural-valve plumbing fixture herein chosen for illustration of the present invention includes a hollow distributing-head 15 which may be conveniently formed by casting 10 and which, in the instance shown, is provided with two corresponding forwardly-projecting externally- and internally-threaded tubular extensions constituting valve-bodies or housings 16 and 17 and respectively located at the upper left-hand corner and upper right-hand corner of the distributing-head, as shown in Fig. 6.

Immediately beneath the integral valve-body 16, the distributing-head 15 is formed with a hollow enlargement 18 corresponding to a similar hollow enlargement 19 formed on the opposite side of the distributing-head immediately below the valve-body 17, before referred to. Horizontally intermediate the hollow enlargements 18 and 19, the distributor-head 15 is 25 formed with a hollow enlargement 20 corresponding to the enlargements 18 and 19 before referred to, the said enlargement 20 being disposed beneath the enlargements 18 and 19 as is particularly well shown in Fig. 6.

The hollow enlargement 18 is joined to the enlargement 20 by an integral web 21 complementary to a web 22 joining the enlargements 19 and 20 together and formed integral therewith.

Leading downwardly from the valve-body or housing 17 of the distributing-head 15 is a cold-water connecting-passage 23, the lower end of which leads to the interior of the enlargement 19 before referred to, and the upper end of which extends beneath an integral partition 24 40 (Figs. 4 and 7). Threaded into the partition 24 is a removable and replaceable tubular valve-seat bushing 25 having a polygonal water-passage 26 leading forwardly to the adjacent end of the horizontal reach 27 of a T-shaped mixing-chamber generally designated by the reference character 28.

Engageable with the forward face of the valve-seat bushing 25 to check or regulate the flow of cold water from the enlargement 19 into 50 the T-shaped mixing-chamber 28 of the distributing-head, is a valve-head 29 provided with an externally-threaded enlarged portion 30 engageable with threads 31 formed in the inner periphery of the valve-body 17 and serving, when 55

rotated by means of a valve-stem 32, to advance and retire the valve-head 29 as a whole toward and away from the valve-seat bushing 25.

The valve-stem 32, above referred to, extends 5 outwardly through a sealing-washer 33, a clamping-washer 34 and a packing-nut 35 and is provided, at its outer end, in any approved manner, with a valve-handle 36. The sealing-washer 33 is preferably formed of indurated fiber and is 10 seated against the outer edge of the valve-body 17 by the clamping-washer 34 which, in turn, is seated against an inwardly-facing clamping-shoulder 37 formed in the packing-nut 35 intermediate a packing-pocket 38 and the internally-threaded skirt 39 thereof. The packing-pocket 38 of the packing-nut 35 is filled with fibrous packing material 40 and the skirt 39 of the packing-nut is threadedly engaged with threads 41 formed upon the outer periphery of the valve-body 17, as is clearly shown in Fig. 4.

The valve mechanism above described and located in the valve-body 17 constitutes, in the structure shown, a cold-water control-valve and, for convenience of description, will be generally 25 designated by the reference character 42. The valve-body 16 is provided with a hot-water control-valve generally designated by the reference character 43, the mechanism of which corresponds to the mechanism of the cold-water control-valve 42, and where parts thereof appear in the drawings, such parts bear similar reference characters.

Leading downwardly from the valve-body or housing 16 of the hot-water control-valve 43 is a 35 hot-water connecting-passage 44, the lower end of which leads to the interior of the enlargement 18. The hot-water control-valve 43, in a manner similar to the cold-water control-valve 42, communicates with the adjacent end of the horizontal arm 27 of the T-shaped mixing-chamber 28.

Extending from front to rear through the enlargement 19 of the distributing-head 15 is a passage 45. Similarly, the enlargement 18 is also provided with a central-passage 46. The passages 45 and 46, respectively formed in the enlargements 19 and 18, each receive one of two corresponding water-inlet connecting-members 47, one of which is especially well shown in Fig. 4. Each of the said water-inlet connecting-members 47 includes a forwardly-projecting externally-threaded stud-like portion 48 and a rearwardly-extending socket 49 having internal threads and receiving the externally-threaded forward end of a water-inlet nipple 50.

Each water-inlet connecting-member 47 is also 55 provided with an axial water-passage 51 communicating at its rear end with the socket 49, and at its forward end the said water-passage 51 is intersected by radial water-passages 52 extending through the adjacent wall of the stud-portion 48 from the outer periphery thereof into communication with the passage 51. The passages 52— 60 52 communicate with the interior of the particular one of the enlargements 18 and 19 in which the given connecting-member 47 is mounted, and hence in communication with the hot-water connecting-passage 44 or cold-water connecting-passage 23 respectively leading into the enlargements 18 and 19.

Each water-inlet connecting-member 47 is 70 formed with an enlarged sealing-flange 53 of rounded form in cross section and adapted to make a substantially line-contact with the sloping surface of a rearwardly-facing conical sealing-seat 54 formed in the rear face of each of the

enlargements 19 and 18 concentrically with the passages 45 and 46 respectively therein. Formed in the forward face of each of the enlargements referred to concentrically with the passages 45 and 46 respectively therein, is a forwardly-facing 5 conical sealing-seat 55 which is engaged by the rounded inner-face 56 of a sealing-nut 57. The said sealing-nut is provided with an internally-threaded socket 58 closed at its forward end by an end-wall 59 and receiving the externally-threaded stud-like portion 48 of the complementary water-inlet connecting-member 47.

By tightening the sealing-nut 57, the sealing-flange 53 of its complementary connecting-member 47 is seated against the conical sealing-seat 15 54 in the rear face of the respective enlargement in which the connecting-member may be mounted, and at the same time, the rounded inner-face 56 of the sealing-nut 57 is firmly seated against the forwardly-facing conical sealing-seat 20 55 in the said enlargement. In this manner the leakage of water from within the distributing-head along the contacting-surfaces 53—54 and 55—56 is effectively prevented.

As before pointed out, each of the connecting-members 47, respectively mounted in the enlargements 18 and 19, has coupled thereto a nipple 50, the rear end of each of which is threaded into an elbow 60. Each of the elbows 60 just referred to, is preferably formed with a polygonal portion 30 61 seated in a similarly-shaped socket 62 formed in a sheet-metal template 63. The externally-threaded portion adjacent the polygonal portion 61 of each of the elbows 60 has threaded thereon a nut 64 to securely hold the elbows 60 in place 35 with respect to the template 63.

The elbow 60 connected to the enlargement 18 has connected to its downwardly-extending arm a hot-water supply-pipe 65 while the elbow 60 connected to the enlargement 19 has secured to 40 its downwardly-extending arm a cold-water supply-pipe 66.

Placed over the distributing-head 15 and concealing the same as well as concealing the inner portions of the two valve-bodies 16 and 17, is a 45 sheet-metal escutcheon or finishing-plate 67 having, in the instance shown, a rearwardly-extending polygonal-flange 68 contacting with the outer surface of a wall 69 and including a substantially-flat front-portion 70 which is provided with two 50 perforations 71, through each of which respectively extend one of the valve-bodies 16 and 17. The front-portion 70 of the escutcheon or finishing-plate 67 is also formed with a perforation 72 located horizontally intermediate the perforations 71. For the purpose of conveniently retaining the escutcheon 67 in place, a cup-shaped retaining-nut 73 is threaded upon the external threads of each of the valve-bodies 16 and 17 respectively. 60

Returning to the enlargement 20, it will be noted that the said enlargement is formed with a central-passage 74 extending from front to rear therethrough, in which is installed a water-outlet connecting-member generally designated 65 by the reference character 75. The water-outlet connecting-member 75 includes a forwardly-projecting externally-threaded stud-like portion 76 (Fig. 3) which is in communication with the T-shaped mixing-chamber 28 in a manner as will 70 hereinafter appear, and a rearwardly-extending internally-threaded socket 77.

The internally-threaded socket 77 of the water-outlet connecting-member 75 receives the externally-threaded forward end of a nipple 78. 75

Opening through the forward face of the stud-like portion 76 and extending axially therethrough is a valve-receiving chamber 79 opening through a passage 80 concentric with the valve-chamber 79 into the socket 77 before referred to. Extending radially through the side wall of the stud-like portion 76 from the outer periphery thereof to the valve-chamber 79, are two radial passages 81 located diametrically opposite to each other. By referring to Figs. 3 and 5 of the drawings, it will be observed that the passages 81 open into the interior of the enlargement 20 and hence into the lower end of the vertical reach 82 of the T-shaped mixing-chamber 28, the said vertical reach being in communication with the interior of the said enlargement 20.

Mounted in the valve-chamber 79 with capacity for turning movement therein is a cylindrical valve-head 83 provided with a relatively slender integral valve-stem 84 to the outer free end of which is coupled for rotation therewith a cup-shaped operating finger-piece 85 having a knurled periphery and held against axial displacement from the said valve-stem by a screw 86. The valve-head 83 is formed with an axial chamber 87 opening through its inner end in axial alignment with the passage 80 formed in the connecting-member 75 and therefore into communication with the internally-threaded socket 77 of the said connecting-member. The side wall of the valve-head 83 is formed with two diametrically-opposite water-outlet ports 88 extending radially from the outer periphery of the said valve-head inwardly to the chamber 87 to intersect the latter. The said outlet-ports 88 are adapted to be brought wholly or partly into registration with the passages 81 formed in the stud-portion 76 of the connecting-member 75 as shown in Figs. 3 and 5.

The inner end of the valve-head 83 is seated against a shoulder 89 at the junction of the valve-chamber 79 and the passage 80 in the connecting-member 75, and is held against axial outward displacement by a helical spring 90 surrounding the valve-stem 84 and located in a recess 91 formed in the end wall of an internally-threaded socket 92 of a sealing-nut 93. One end of the spring 90 thrusts against the end wall of the recess 91 while the other end thereof thrusts against the adjacent forward face of the valve-head 83, the said spring serving to constantly but yieldingly hold the inner end of the valve-head 83 seated against the shoulder 89 to thus insure the ports 88 being axially in line with the passages 81.

The water-outlet connecting-member 75 is formed with an enlarged sealing-flange 94 of rounded form in cross section and adapted in a manner similar to the water-inlet connecting-member 47 before referred to, to make a substantially line contact with the sloping surface of a rearwardly-facing conical sealing-seat 95 formed in the rear face of the enlargement 20 concentrically with the passage 74 therein. The forward face of the enlargement 20 is formed concentrically with the passage 74 therein, with a conical sealing-seat 96 in opposition and complementary to the sealing-seat 95, and which is engaged by the rounded inner face 97 of the sealing-nut 93 before referred to.

The sealing-nut 93 has its threaded socket 92 receiving the externally-threaded stud-like portion 76 of the complementary water-outlet connecting-member 75, and by tightening the sealing-nut 93, the sealing-flange 94 of the connect-

ing-member 75 is seated against the conical sealing-seat 95 in the rear face of the enlargement 20. At the same time, the rounded inner face 97 of the sealing-nut 93 is firmly seated against the forwardly-facing conical sealing-seat 96 in the said enlargement. In this manner the leakage of water from within the distributing-head past the contacting-surfaces 94-95 and 96-97, is effectively prevented.

The sealing-nut 93 is formed with a forwardly-extending sleeve 98 which is both internally and externally threaded and which projects forwardly through the perforation 72 before referred to, in the finishing-plate 61. The valve-stem 84 extends forwardly through, and has bearing in, a bearing-passage 99 axially formed in the sleeve 98, and is surrounded by packing material 100 located in the said sleeve 98 and compressed therein by a gland-nut 101 which is threaded within the said sleeve 98. Removably threaded upon the exterior of the sleeve 98 is a retaining-nut 102 provided with a knurled periphery, and also having a radially-extending flange 103 which bears against the front face of the escutcheon 67 and serves to provide a finishing member which conceals the external threads upon the sleeve 98 of the sealing-nut 93. The parts just above described constitute what may for convenience of description be called a volume-control valve 104.

As before pointed out, the water-outlet connecting-member 75 has coupled thereto a nipple 78, the rear end of which is threaded into an elbow 105 which is formed with a polygonal portion 106 seated in a similarly-shaped locating-socket 107 in the sheet-metal template 63 before described. The elbow 105 is retained in place with respect to the template 63 by a retaining-nut 108 and has coupled to its upwardly-extending arm a pipe 109 leading to a shower-head or the like.

The particular plural-valve plumbing fixture herein chosen for illustration provides for either selectively supplying hot or cold water or supplying a mixture of both hot and cold water to a shower head or the like, as will be obvious from the foregoing description and the accompanying drawings. Thus, for instance, should the valves 42 and 43 be simultaneously opened, both hot and cold water will be mixed in the mixing-chamber 28 to any desired temperature by manipulating the valves 42 and 43 and will flow upwardly through the pipe 109 to the shower-head when the parts constituting the volume-control valve 104 are in the positions in which they are shown in Figs. 3 and 5.

With the ports 88 formed in the valve-head 83 of the volume-control valve 104 in full registration with the passages 81 of the stud-like portion 76 forming part of the connecting-member 75, as shown in Figs. 3 and 5, water will flow outwardly from the mixing-chamber 28 and the interior of the enlargement 20 through the passages 81 and the ports 88 into the chamber 87 formed in the valve-head 83, and hence from there through the passage 80 out through the nipple 78 and the pipe 109 to the shower-head at its maximum or greatest flow.

If it should be desired to reduce the volume or flow of water from the distributing-head to the shower-head without affecting or changing the relative amounts of hot and cold water delivered to the mixing-chamber 28, the same may be accomplished by rotating the operating-finger-piece 85 to thus turn the valve-head 83 with re-

spect to the stud-like portion 76 of the connecting-member 75. This turning movement will move the ports 88 of the valve-head 83 out of full registration with the passages 81 formed in the said stud-like portion. By moving the ports 88 out of full registration with the passages 81, the said ports will be closed off reducing their effective size to thereby reduce the volume or flow of water passing therethrough to the shower-head. It will be understood, of course, that the ports 88 may be moved out of registration with the passages 81 any degree desired to efficiently and accurately control or regulate the volume of water flowing from the distributor-head to the shower-head.

From the foregoing it will be understood that by manipulating the valves 42 and 43, the hot water and cold water may be mixed together to any desired temperature in the mixing-chamber 28, and that the volume of water flowing from the distributor-head to the shower may be effectively and easily regulated by the volume-control valve 104 without changing the selected temperature of the water.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A plural-valve plumbing fixture including in combination: a hollow distributing-head having a hot-water inlet, a cold-water inlet, a T-shaped mixing-chamber communicating with the said hot-water inlet and the said cold-water inlet, hot-water-valve-receiving means interposed between the said hot-water inlet and the said T-shaped mixing-chamber, cold-water-valve-receiving means located intermediate the said cold-water inlet and the said T-shaped mixing-chamber, and a mixed-water outlet comprising volume-control-valve-receiving means having an axial passage enlarged intermediate the respective opposite ends thereof to provide a flow-chamber in the said distributing-head communicating with the said T-shaped mixing-chamber thereof; a hot-water-control valve mounted in the hot-water-valve-receiving means of the said distributing-head; a cold-water-control valve installed in the cold-water-valve-receiving means of the said distributing-head; and a volume-control valve installed in the volume-control-valve-receiving means of the said distributing-head and constructed and arranged to be selectively disposed at full-open position, full-shut position, and intermediate positions with respect to the said flow-chamber to control the outflow therefrom of hot and cold water mixed in the T-shaped mixing-chamber of the said distributing-head.

2. A plural-valve plumbing fixture including in combination: a hollow distributing-head having a hot-water inlet, a cold-water inlet, a mixing-chamber communicating with the said hot-water inlet and cold-water inlet, a hot-water-valve housing projecting from the distributing-head intermediate the hot-water inlet and the mixing-chamber, a cold-water-valve housing projecting from the distributing-head at a point intermediate the said cold-water inlet and the said mixing-chamber, and a mixed-water outlet comprising

volume-control-valve-receiving means having an axial passage enlarged intermediate the respective opposite ends thereof to provide a flow-chamber in the said distributing-head communicating with the said mixing-chamber thereof; a hot-water-control valve mounted in the hot-water-valve housing of the said distributing-head; a cold-water-control valve installed in the cold-water-valve housing of the said distributing-head; and a volume-control valve installed in the volume-control-valve-receiving means of the said distributing-head and surrounded by the flow-chamber thereof, the said volume-control valve being constructed and arranged to be selectively disposed in full-open position, full-shut position and intermediate positions with respect to the said flow-chamber to control the outflow therefrom of hot and cold water mixed in the mixing-chamber of the said distributing-head.

3. A plural-valve plumbing fixture including in combination: a hollow distributing-head having a hot-water inlet, a cold-water inlet, a T-shaped mixing-chamber communicating with the said hot-water inlet and cold-water inlet, a hot-water-valve housing projecting from the distributing-head intermediate the hot-water inlet and the T-shaped mixing-chamber, a cold-water-valve housing projecting from the distributing-head at a point intermediate the said cold-water inlet and the said T-shaped mixing-chamber, the latter having a lateral inlet-branch thereof communicating with each of the respective valve-housings, and a mixed-water outlet comprising volume-control-valve-receiving means communicating with a vertically-disposed outlet-branch of the said T-shaped mixing-chamber; a hot-water-control valve mounted in the hot-water-valve housing of the said distributing-head at the open end of one of the lateral inlet-branches of the T-shaped mixing-chamber thereof; a cold-water-control valve installed in the cold-water-valve housing of the said distributing-head at the open end of the other of the lateral inlet-branches of the T-shaped mixing chamber thereof; and a volume-control valve installed in the volume-control-valve-receiving means of the said distributing-head at the open end of the vertical outlet-branch of the T-shaped mixing-chamber to control the outflow from the said distributing-head of hot and cold water mixed in the T-shaped mixing-chamber thereof.

4. A plural-valve plumbing fixture including in combination: a hollow distributing-head having a hot-water inlet, a cold-water inlet, a mixed-water outlet having a volume-control-valve receiving passage extending therethrough from front to rear and enlarged intermediate the respective opposite ends thereof to provide a flow-chamber, and a mixing-chamber communicating with the said hot-water inlet and cold-water inlet and flow-chamber of the said distributing-head; a hot-water-control valve mounted in the distributing-head intermediate the hot-water inlet and the mixing-chamber thereof; a cold-water-control valve mounted in the distributing-head intermediate the cold-water inlet and the mixing-chamber thereof; and a volume-control valve installed in the volume-control-valve passage of the said distributing-head and surrounded by the said flow-chamber, the said volume-control valve being provided with a plurality of passages for communicably connecting the interior thereof with the flow-chamber of the said distributing-head and being constructed and arranged to be selectively disposed in full-open position, full-shut position and intermediate positions with respect to the said flow-chamber to control the outflow therefrom of hot and cold water mixed in the mixing-chamber of the said distributing-head.

position, full-shut position and intermediate positions with respect to the said flow-chamber to control the outflow therefrom of hot and cold water mixed in the mixing-chamber of the said distributing-head.

5. A plural-valve plumbing fixture including in combination: a hollow distributing-head having a hot-water inlet, a cold-water inlet, a mixed-water outlet having a volume-control-valve passage 10 extending therethrough from front to rear, and a mixing-chamber communicating with the said hot-water inlet and cold-water inlet and volume-control-valve passage; a hot-water-control valve mounted in the distributing-head intermediate the hot-water inlet and the mixing-chamber 15 thereof; a cold-water-control valve mounted in the distributing-head intermediate the cold-water inlet and the mixing-chamber thereof; a valve-housing removably installed in the volume-control-valve passage of the said distributing-head 20 and having an axial valve-head-receiving socket therein communicating laterally with the mixing-chamber of the said distributing-head and communicating axially at one end with the mixed-water outlet of the said distributing-head; 25 and a rotary volume-control valve-head installed in the socket in the said valve-housing and rotatable to control the flow of water therethrough from the mixing-chamber of the said distributing-head to the mixed-water outlet of the said distributing-head.
25. an open end of the second of the two intercommunicating lateral inlet-branches of the T-shaped mixing-chamber; and a volume-control valve installed in the volume-control-valve passage of the said distributing-head adjacent an open end of 30 an outlet-branch of the T-shaped mixing-chamber communicating with the respective lateral inlet-branches and extending vertically therefrom, the said volume-control valve being constructed and arranged to be selectively disposed 35 in full-open position, full-shut position and intermediate positions with respect to the said flow-chamber of the distributing-head to control the outflow therefrom of hot and cold water mixed in the T-shaped mixing-chamber of the said distributing-head.
40. 6. A plural-valve plumbing fixture including in combination: a hollow distributing-head having a hot-water inlet, a cold-water inlet, a mixed-water outlet having a volume-control-valve passage 45 extending therethrough from front to rear, and a mixing-chamber communicating with the said hot-water inlet and cold-water inlet and volume-control-valve passage; a hot-water-control valve mounted in the distributing-head intermediate the hot-water inlet and the mixing-chamber 50 thereof; a cold-water-control valve mounted in the distributing-head intermediate the cold-water inlet and the mixing-chamber thereof; a valve-housing installed in the volume-control-valve passage of the said distributing-head and having an axial valve-receiving socket therein, a radial port extending from the valve-receiving socket into communication with the mixing-chamber of the said distributing-head, and an outlet-port through one of its ends in communication with the mixed-water outlet of the said distributing-head; and a rotary volume-control 55 valve-head mounted for rotation in the valve-receiving socket of the said valve-housing and having an axial water-passage communicating with the outlet-port of the said valve-housing and also having a radial port connecting its axial water-passage with the radial port in the said valve-housing.
55. 7. A plural-valve plumbing fixture including in combination: a hollow distributing-head having a hot-water inlet, a cold-water inlet, a mixed-water outlet, a volume-control-valve passage extending therethrough from front to rear, two oppositely-facing seats respectively at the respective opposite ends of the said control-valve passage, and a mixing-chamber communicating with the said hot-water inlet and cold-water inlet and volume-control-valve passage; a hot-water-control valve mounted in the distributing-head intermediate the hot-water inlet and the mixing-chamber 60 thereof; a cold-water-control valve mounted in the distributing-head intermediate the cold-water inlet and the mixing-chamber thereof; a valve-housing removably installed in the volume-control-valve passage of the said distributing-head and having an axial valve-head-receiving socket therein communicating laterally with the mixing-chamber of the said distributing-head and communicating axially at one end 65
70. 75. against axial displacement.

7. A plural-valve plumbing fixture including in combination: a hollow distributing-head having a hot-water inlet, a cold-water inlet, a mixed-water outlet, a volume-control-valve passage extending therethrough from front to rear, and a mixing-chamber communicating with the said hot-water inlet and cold-water inlet and volume-control-valve passage; a hot-water-control valve mounted in the distributing-head intermediate the hot-water inlet and the mixing-chamber 10 thereof; a cold-water-control valve mounted in the distributing-head intermediate the cold-water inlet and the mixing-chamber thereof; a valve-housing removably installed in the volume-control-valve passage of the said distributing-head 15 and having an axial valve-head-receiving socket therein communicating laterally with the mixing-chamber of the said distributing-head and communicating axially at one end with the mixed-water outlet of the said distributing-head; 20 and a rotary volume-control valve-head installed in the socket in the said valve-housing and rotatable to control the flow of water therethrough from the mixing-chamber of the said distributing-head to the mixed-water outlet of the said distributing-head.

8. A plural-valve plumbing fixture including in combination: a hollow distributing-head having a hot-water inlet, a cold-water inlet, a mixed-water outlet, a volume-control-valve passage extending therethrough from front to rear, and a mixing-chamber communicating with the said hot-water inlet and cold-water inlet and volume-control-valve passage; a hot-water-control valve mounted in the distributing-head intermediate the hot-water inlet and the mixing-chamber 30 thereof; a cold-water-control valve mounted in the distributing-head intermediate the cold-water inlet and the mixing-chamber thereof; a valve-housing installed in the volume-control-valve passage of the said distributing-head and having an axial valve-receiving socket therein, a radial port extending from the valve-receiving socket into communication with the mixing-chamber of the said distributing-head, and an outlet-port through one of its ends in communication with the mixed-water outlet of the said distributing-head; and a rotary volume-control 35 valve-head mounted for rotation in the valve-receiving socket of the said valve-housing and having an axial water-passage communicating with the outlet-port of the said valve-housing and also having a radial port connecting its axial water-passage with the radial port in the said valve-housing.

9. A plural-valve plumbing fixture including in combination: a hollow distributing-head having a hot-water inlet, a cold-water inlet, a mixed-water outlet, a volume-control-valve passage extending therethrough from front to rear, two oppositely-facing seats respectively at the respective opposite ends of the said control-valve passage, and a mixing-chamber communicating with the said hot-water inlet and cold-water inlet and volume-control-valve passage; a hot-water-control valve mounted in the distributing-head intermediate the hot-water inlet and the mixing-chamber 60 thereof; a cold-water-control valve mounted in the distributing-head intermediate the cold-water inlet and the mixing-chamber thereof; a valve-housing removably installed in the volume-control-valve passage of the said distributing-head and having an axial valve-head-receiving socket therein communicating laterally with the mixing-chamber of the said distributing-head and communicating axially at one end 65

70. 75. against axial displacement.

with the mixed-water outlet of the said distributing-head; a rotary volume-control valve-head installed in the socket in the said valve-housing and rotatable to control the flow of water there-
5 through from the mixing-chamber of the said distributing-head to the mixed-water outlet of the said distributing-head; and two clamping-members carried by the said valve-housing and respectively engaging one of the two oppositely-
10 facing seats of the said distributing-head.

10. A plural-valve plumbing fixture including in combination: a hollow distributing-head having a hot-water inlet, a cold-water inlet, a mixed-water outlet, a volume-control-valve passage ex-
15 tending therethrough from front to rear, two op-
positely-facing seats respectively at the respec-
tive opposite ends of the said control-valve pas-
sage, and a mixing-chamber communicating with
the said hot-water inlet and cold-water inlet and
20 volume-control-valve passage; a hot-water-con-
trol valve mounted in the distributing-head inter-
mediate the hot-water inlet and the mixing-
chamber thereof; a cold-water-control valve
25 mounted in the distributing-head intermediate
the cold-water inlet and the mixing-chamber
thereof; a valve-housing installed in the volume-
control-valve passage of the said distributing-
head and having an axial valve-receiving socket
30 therein, a radial port extending from the valve-
receiving socket into communication with the
mixing-chamber of the said distributing-head, and
an outlet-port through one of its ends in
communication with the mixed-water outlet of
35 the said distributing-head; a rotary volume-con-
trol valve-head mounted for rotation in the
valve-receiving socket of the said valve-housing
and having an axial water-passage therein com-
municating with the outlet-port of the said valve-
40 housing and also having a radial port connecting
its axial water-passage with the radial port in
the said valve-housing; and two clamping-mem-
bers carried by the said valve-housing and re-
spectively engaging one of the two oppositely-
facing seats of the said distributing-head.

11. A plural-valve plumbing fixture including in combination: a hollow distributing-head hav-
ing a plurality of control-valves organized there-
with and controlling the flow of water thereto,
and also having a mixing-chamber therein and
a water-outlet passage extending through the
said distributing-head substantially perpendic-
ular thereto and in communication with the said
mixing-chamber; a connecting-member coupled
to a piping system and having a projecting por-
tion extending into the water-outlet passage in
the said distributing-head and also having an 15
axial chamber therein communicating with the
mixing-chamber in the said distributing-head,
the said connecting-member also having a por-
tion in sealing engagement with the rear wall
of the said distributing-head; a clamping-mem-
ber connected to the said connecting-member
and having a passage extending axially there-
through and also having a portion in sealing en-
gagement with the front wall of the said dis-
tributing-head; and a volume-control valve hav-
ing a hollow valve-head axially mounted with
capacity for turning movement in the said con-
necting-member and having one end thereof
yieldingly engaging a portion of the said con-
necting-member and having an operating-stem 30
extending forwardly through the axial passage in
the said clamping-member, the interior of the
valve-head being in communication with the said
piping system, the said valve-head also having
water-passages in communication with the in-
terior thereof and with the mixing-chamber of
the said distributing-head, the said volume-con-
trol valve serving to regulate the volume of flow
of water from the mixing-chamber in the said
distributing-head to a shower fixture. 49
